FLOATING ROOF

Frederick D. Moyer, Chicago, Ill., assignor to Chicago Bridge & Iron Company, a corporation of Illinois.

Application September 30, 1949, Serial No. 118,810

3 Claims. (Cl. 220—26)

1

This invention relates to a floating roof for use in a liquid storage tank.

Floating roofs of many types and forms have been proposed and used in tanks designed for the storage of volatile liquids. In general, the roofs fall into two classifications, namely, single deck roofs in which a flat deck of sheet metal is floated upon the surface of the liquid in the tank or supported above the surface by one or more pontoons, and double deck roofs. In the double deck form of construction, two decks are provided, one usually in contact with the stored product and the other spaced above the bottom deck to provide an insulating air space. This latter type of roof is particularly useful in areas where high daily temperatures are encountered and where the product stored is quite volatile in nature. Where extreme conditions are not encountered, a single deck roof is more economical to construct and is generally preferred for use.

The construction of a roof of either the single or double deck type presents a rather difficult problem inasmuch as the plates forming the deck proper must be supported on temporary framing located within the tank during construction. Such framing is generally constructed of wood beams supported on temporary wood or metal supports over which the deck plates are laid and welded or otherwise secured together.

A single deck roof of the pan type, that is, one which supports itself on the liquid by the use of a rim upstanding around the edge, while being one of the least expensive to construct, is subject to flexing difficulties in that pontoons (which serve not only to support the roof but also to stiffen it) are omitted. Furthermore, pan type roofs are subject to considerable flexing when resting on supports on the bottom of the tank when the tank is empty.

I have invented a pan type floating roof which because of its particular construction is not only more simple to assemble initially but also possesses great resistance to flexing during all phases of operation.

The invention will be described in conjunction with the accompanying drawings in which

Fig. 1 is a top plan view of a floating roof tank including the roof of this invention.

Fig. 2 is a side elevation of the apparatus shown in Fig. 1 with the lower portion of the tank broken away;

Fig. 3 is a vertical section, broken into segments, through a portion of the roof;

Fig. 4 is a top plan view of the right hand portion of Fig. 3;

2

Fig. 5 is a vertical section along line 5—5 of Fig. 3; and

Fig. 6 is an enlarged detailed view of a portion of the trusswork on the roof.

Referring now to the drawings, I show a floating roof tank 10 having a pan type roof 11 constructed according to this invention, located therein. The roof comprises a flat deck portion 12 supported on a plurality of radial girders 13. The girders, a number of which are provided, radiate outwardly from the center 14 of the roof. A circular rim 15 is secured to the outer edges of the girders and the deck and is supported in upstanding position above the deck by triangular plates 16 having one edge welded to the rim and another edge welded to the deck. A plurality of inner posts 17 and outer posts 17a extend through the deck and through the girders and have their lower end portions 18 located beneath the deck and girder structure. Each post consists of a pipe member 19 which extends through the deck and girders and has a pair of angle irons 20 welded to its upper end. A second pipe section 21 is welded to the upper ends of the angle irons and is provided with brackets 22 and 23 extending therefrom along a radius of the deck.

A truss system 24 extends from a central metallic disc 25 positioned on the upper end of a post 26 extending from the center portion of the deck. Each truss system consists of a first cable 27 extending between the disc 25 and each inner post 17, a second cable 28 extending between the post 17 and the post 17a, and a pair of cables 29 and 30 extending divergently outward from the outer post 17a to two of the plates 16.

A trusswork 32 connects the posts 17 to each other and consists of steel rods 33 welded or otherwise secured to the lower portion of a post 17 and extending diagonally upward to the upper portion of an adjoining post 17. As can be seen in Figs. 2 and 6, alternate pairs of posts 17 are provided with the X type trusswork shown in the right hand portion of Fig. 6, while intermediate pairs of posts 17 are connected by a single rod 33 as seen in the left hand portion of Fig. 6.

Means are provided for preventing the roof from rotating within the tank during its operation, the means comprising in the embodiment shown a channel member 34 running vertically from the top to the bottom of the tank engaging the sides of a cut-out portion 35 in the roof.

In constructing the roof of this invention, the temporary framing members 36 are first placed into position on the bottom 37 of the tank. The temporary framing members may be left in the

tank to support the roof during periods of operation when it is not floating on the liquid or they may be subsequently replaced by permanent supports of similar construction. Next, the radial girders 13 are located in position on the supports and the plates forming the deck 12 are laid thereon and welded or otherwise secured thereto. Thus, it can be seen that all or practically all of the temporary girders needed in the framing for constructing the roof are eliminated and the radial girders used for framing eventually become an integral part of the roof. The plates 16 may then be secured in position on the deck, the rim attached and the other details of the roof completed.

In the operation of the roof the truss system and trusswork described herein serve not only to support the roof against flexure but also sup-

In addition, strict control measures should be implemented to prevent the spread of the disease among the population.

a central post with all the inner posts being equidistant from the central post, a trusswork interconnecting the inner posts and a truss system connecting radially aligned posts with the rim and being connected together at the center of the roof above the deck.

2. A circular floating roof comprising a plurality of girders connected together and adapted to resist torsional stresses in the roof, a deck on the upper side of the girders, a circular rim attached to the outer ends of the girders and upstanding from the deck, a plurality of posts attached to each girder and extending above and below the deck, said posts including an inner post, an outer post attached to each girder and a central post with all the inner posts being equidistant from the central post, the outer posts being
